United States Patent Office.

HENRY M. MYERS, OF ALLEGHENY CITY, PENNSYLVANIA.

Design No. 3,118, dated July 21, 1868.

DESIGN FOR A TRADE-MARK.

The Schedule referred to in these Letters Patent and making part of the same.

TO ALL WHOM IT MAY CONCERN:

Be it known that I, HENRY M. MYERS, of the city and county of Allegheny, in the State of Pennsylvania, have originated and designed a new Design for a Trade-Mark for axes, embracing the configuration of the coloring and letters, of which the following is a full, clear, and exact description, reference being had to the accompanying drawings, making part of this specification.

In the accompanying drawings—

Figure 1 represents the right-hand side of an ordinary axe provided with my improved design for a trade-mark.

Figure 2 represents the left-hand side of the same.

After the axe has been ground, buffed, and completely finished, I paint a part of the axe, as represented in the accompanying drawings. After the paint becomes dry, I attach, by any known means, a label of the form, and provided with the letters, configurations, and finish, clearly described and shown in the accompanying drawings.

Having thus fully and clearly described my design for a trade-mark, what I claim as of my invention, and desire to secure by Letters Patent, is—

The design for a trade-mark, embracing the configuration of the coloring and label of an axe, substantially as herein shown and described.

H. M. MYERS.
